UNITED STATES PATENT OFFICE.

FRANK DANIELSON, OF CHICAGO, ILLINOIS.

UNIVERSAL BURNING-IN AND RUNNING-IN MACHINE.

1,369,223.

Specification of Letters Patent. Patented Feb. 22, 1921.

Application filed July 10, 1918. Serial No. 244,154.

To all whom it may concern:

Be it known that I, FRANK DANIELSON, a citizen of the United States, residing at Chicago, in the county of Cook and State 5 of Illinois, have invented certain new and useful Improvements in Universal Burning-In and Running-In Machines, of which the following is a specification.

This invention relates to a machine for 10 burning-in and running-in internal combustion engines and has for its primary object the provision of a machine of universal character adapted to support all types and kinds of internal combustion engines during the 15 operation of burning-in the bearings and also to support the engine after it has been finally assembled while running-in to limber the bearings and detect any oil leakage at the joints of the casing.

20 Further objects and advantages of my invention reside in the various combinations hereinbefore described and claimed as will be better understood by reference to the following specification when read in connection 25 with the accompanying drawing illustrating the preferred embodiment thereof, in which—

Figure 1 is a side elevation of the invention with an engine in position for burning- 30 in the bearings;

Fig. 2 is a plan view of the invention;

Fig. 3 is an enlarged sectional view on the line 3—3 of Fig. 1;

Fig. 4 is a detail sectional view on the 35 line of the bolt 16 in Fig. 3, and

Fig. 5 is a sectional view showing a Ford engine in reverse position arranged in the machine for the burning-in operation.

Heretofore machines have been designed 40 and constructed to perform the separate operations of burning-in and running-in the bearings and these machines have been particularly adapted to engines of specific types and not available for general use. Such machines are relatively expensive and where work on a variety of different engines is contemplated it has been necessary to provide different machines for each type. The essential idea of my invention is the provision 45 of a machine to perform both the burning-in and running-in operations and which is adaptable for use in connection with numerous types of engines through the simple substitution of a specially designed supporting 50 block for each type.

Referring to the drawing, 5 indicates a

frame or bed having supports 6 and 7 for the bearings 8 in which an arbor 9 is rotatably mounted. A multiple speed pulley 10 is supported on the arbor 9 and is adapted to be 60 connected thereto by means of a clutch 11 of any suitable or well known form and controllable by a clutch lever 12. The multiple speed pulley 10 permits rotation of the arbor 9 selectively at different speeds, it being 65 necessary to rotate the arbor at a speed higher during the running-in operation than during the burning-in operation.

The center line of the arbor 9 is preferably 70 spaced from the bed sufficiently to permit connection with the shaft 13 of the engine 14 when the latter is reversed and resting on its head as indicated in Fig. 5 to permit closer inspection of the bearings during the 75 burning-in operation. This of course necessitates designing a machine particularly for one type of engine, as for example the Ford. The utility of the machine may be greatly augmented, however, by providing interchangeable means for supporting any of 80 the other types of engines. I therefore, provide a separable block 15 adapted to receive and support the engine 14 in upright position with the shaft 13 in alinement with the arbor 9. The block 15 is held on the bed 5 85 by a bolt 16 and is provided with laterally projecting lugs 17 to receive bolts 18 threaded at their upper ends and provided with clamping heads 19 which hold a bar 20 in engagement with the engine head whereby 90 the engine is clamped on the block 15. A plurality of blocks 15 are provided each of which is adapted to support a particular type of engine with its shaft in alinement with the arbor 9 and by substituting a suitable block 15 any engine found in the trade 95 may be supported and held in proper working relation in the machine for burning-in the bearings.

After the burning-in operation the engine 100 is completely assembled, the lower half of the crank case and speed changing mechanism being secured to the cylinder block. The engine is then replaced in the machine for the running-in operation to limber the bearings and to discover any oil leakage. The machine is provided with a three point support for the engine during the running-in operation comprising a rigid arm 21 projecting from the end of the bed 5 opposite the 105 arbor 9 and an adjustable support 22 having two arms 23. The support 22 is mounted in

a transverse groove 24 in the bed 5 which is provided with a slot 25 to receive bolts 26 threadedly engaging the support 22. Screws 27 also threadedly mounted in the support 22 and engaging the bottom of the groove 24 in the bed permit vertical adjustment of the support 17 relatively to the bed. A slot 28 is provided in the support 22 to permit the bolt 16 holding the block 15 in place to pass therethrough.

As will be readily understood by manipulating the bolts 26 and screws 27 the arms 23 may without machining be adjusted transversely and vertically with respect to the bed 5 to properly level and center the arms so that the shaft of any engine supported on the arms 21 and 23 will aline with the arbor 9. This adjustment when once made is not thereafter disturbed.

20 The arm 21 is provided with a clamp 29 pivoted at 30 and engaging a screw 31 having a clamping head 32. The end of the clamp 29 is slotted and the screw 31 is pivoted to permit disengagement of the clamp and screw when the clamping head 32 is released. Pivoted yokes 33 having clamping screws 34 are mounted on the arms 23. The clamp 29 and screws 34 engage projections on the engine to lock it in the machine during the 30 running-in operation.

A clamping bar 35 (Fig. 5) adapted to be secured to the arms 23 by suitable connecting devices holds a Ford engine in inverted position on the bed 5 during the burning-in 35 operation. As previously pointed out a single type of engine can be so arranged on the base with its shaft in alinement with the arbor 9. For this as well as other types, interchangeable blocks 15 may be used. In 40 the commercial manufacture of my machine I have constructed it to receive a Ford engine in reverse position for burning-in, as shown in Fig. 5. Suitable blocks 15 are supplied to enable the machine to receive any 45 other type of engine, and also the Ford, in upright position for burning-in. All engines are supported in upright position in the three arms 21, 23, 23, for running-in.

From the foregoing it will be readily 50 understood that I have perfected a machine capable of use in carrying out two separate operations which have heretofore required different machines and which is adapted for operations in connection with different types 55 of engines whereas it has been previously necessary to design separate machines for handling each type of engine. My invention is compact and capable of rigidly supporting the engine during the various operations and materially facilitates the work 60 of finishing the bearings and placing them in condition for use.

Various changes within the scope of the 65 accompanying claims, may be made in the form, construction, and arrangement of the

parts without departing from the spirit of the invention or sacrificing any of its material advantages, the form hereinbefore described being merely a preferred embodiment thereof.

70

I claim:

1. In a machine of the character described the combination of a bed, a rigid arm at one end of said bed, a support carried by said bed and adjustable transversely and vertically thereon, said support having two arms spaced from said rigid arm and from each other, and a rotatable arbor mounted above said bed at the end remote from said rigid arm.

75

2. In a machine of the character described the combination of a bed, having a transverse groove, a rigid arm at one end of said bed, a support carried in said groove and adjustable transversely and vertically on said bed, 85 said support having two arms spaced from said rigid arm and from each other, and means above said bed to engage and rotate the shaft of an internal combustion engine supported on said arms.

80

3. In a machine of the character described the combination of a bed having a transverse groove and a slot in the bottom of said groove, a support slidable in said groove and having two arms, means in said slot to lock 95 said support in transversely adjusted position, means for adjusting said support vertically with respect to said bed, a rigid arm at one end of said bed spaced from said support and a rotatable arbor at the other end of 100 said bed.

90

4. In a machine of the character described the combination of a bed having a transverse groove and a slot in the bottom of said groove, a support slidable in said groove and having two arms, means in said slot to lock 105 said support in transversely adjusted position, a plurality of screws in said support engaging the bottom of said groove whereby said support is adjusted vertically with respect to said bed, a rigid arm at one end of said bed spaced from said support and a rotatable arbor at the other end of said bed.

110

5. In a machine of the character described the combination of a bed, a support transversely adjustable relatively to said bed and having a pair of arms, a plurality of screws in said support and engaging said bed whereby said support is adjusted vertically 115 with respect to said bed, a rigid arm at one end of said bed and spaced from said support and a rotatable arbor at the other end of said bed.

115

6. In a machine of the character described the combination of a bed having a transverse groove and a slot in the bottom of said groove, a support slidable mounted in said groove and having a pair of spaced arms, screws in said support engaging the bottom of said groove whereby said support 125 130

is adjusted vertically with respect to said bed, screws in said slot connecting said support and bed whereby the former is locked in transversely adjusted position relatively 5 to the latter, a rigid arm at one end of said bed and spaced from said support and a rotatable arbor at the other end of said bed.

7. In a machine of the character described the combination of a bed, a rigid arm at one 10 end of said bed, two arms spaced from said rigid arm and from each other and transversely and vertically adjustable relatively to said bed, clamping means on the upper ends of said arms and a rotatable arbor at 15 the end of said bed remote from said rigid arm.

8. In a machine of the character described, the combination of a bed, two spaced arms supported on said bed in trans- 20 versely and vertically adjustable relation thereto, a rigid arm on said bed spaced from the first mentioned arms and a rotatable arbor on said bed opposite said rigid arm.

9. In a machine of the character de- 25 scribed, the combination of a relatively fixed bed, a rotatable arbor supported above said bed at one end thereof, a block mounted on said bed to support an internal combustion engine with its shaft in alinement with said arbor, and means engaging the block at its 30 bottom and the bed for securing the block on said bed.

10. In a machine of the character de- 35 scribed, the combination of a relatively fixed bed, a rotatable arbor supported above said bed, a block mounted on said bed to support an internal combustion engine with its shaft in alinement with said arbor, and means at the top of the block for securing 40 the engine thereto.

11. In a machine of the character de- 45 scribed, the combination of a bed, a rotatable arbor spaced from said bed at one end thereof, three spaced arms to support a complete internal combustion engine with its shaft in alinement with said arbor and a block adapted to rest on said bed and to support a portion of said engine with the shaft in alinement with said arbor, said 50 block being removable to permit mounting of the engine on said arms.

12. In a machine of the character de- 55 scribed, the combination of a bed, a rotatable arbor spaced from said bed at one end thereof, three spaced arms to support a complete internal combustion engine with its shaft in alinement with said arbor, two of said arms being transversely and vertically adjustable relatively to said bed, and a 60 block adapted to rest on said bed and to support a portion of said engine with the shaft in alinement with said arbor, said block being removable to permit mounting of the engine on said arms.

13. In a machine of the character de-

scribed, the combination of a bed, a rotatable arbor spaced from said bed at one end thereof, a removable block on said bed to support an internal combustion engine with its shaft in alinement with said arbor, means 70 engaging the bed for securing the block thereon, lugs on the side of said block, a cross bar and bolts engaging said lugs and cross bar for holding the engine on the block. 75

14. In a machine of the character de- scribed, the combination of a bed, a rotatable arbor spaced from said bed at one end thereof, a rigid arm at the other end of the bed providing an end support disposed opposite the arbor, and a transverse support mounted on the bed and having upwardly extending arms providing supports intermediate the arbor and the end support, said end and intermediate supports providing a 80 three-point support for an internal combustion engine with its shaft in juxtaposition to said arbor. 85

15. In a machine of the character de- scribed, the combination of a bed, a rotatable arbor spaced above said bed at one end thereof, a rigid arm mounted on the bed at the other end thereof to provide an end support disposed opposite the arbor, a pair of arms mounted on the bed and projecting upward at the sides thereof between the arbor and the end support, said end support and arms providing a three-point support for an internal combustion engine with its shaft in juxtaposition to said arbor, and pivoted 90 means on the end support and arms for securing the engine in place thereon. 95

16. In a machine of the character de- scribed the combination of a bed, a rigid arm at one end of said bed, a support carried by said bed and adjustable transversely and vertically thereon, said support having two arms spaced from said rigid arm and from each other, and a rotatable arbor mounted above said bed at the end remote 100 from said rigid arm, said rigid arm and said adjustable arms being provided with adjustable clamping members, and a removable cross bar extending between said adjustable arms. 105

17. In a machine of the character de- scribed the combination of a fixed bed, a rotatable arbor supported above said bed at one end thereof, a block detachably mounted on said bed to support an internal combustion engine having the lower portion of its crank case removed with its shaft in alinement with said arbor, said block being provided with portions at opposite sides thereof for receiving the flanges on the upper portion of the engine crank case thereon and having a recess between said portions to receive the portions of said engine below said flanges therein and means on said block for clamping said engine in position thereon. 110 115 120 125 130

18. In a machine of the character described the combination of a fixed bed, a rotatable arbor supported above said bed at one end thereof, a hollow block detachably mounted on said bed to support an internal combustion engine having the lower portion of its crank case removed with its shaft in alinement with said arbor, said block having a base and upwardly extending side walls 10 adapted to receive the flanges on the upper portion of the engine crank case thereon, and providing a space therebetween to receive the portions of said engine below said flanges therein, and means on said block for 15 clamping said engine in position thereon.

19. In a machine of the character described the combination of a fixed bed, a ro-

tatable arbor supported above said bed at one end thereof, a block detachably mounted on said bed to support an internal combustion engine having the lower portion of its 20 crank case removed with its shaft in alinement with said arbor, said block being provided with portions at opposite sides thereof for receiving the flanges on the upper portion of the engine crank case thereon and having a recess between said portions to receive the portions of said engine below said flanges therein and means for clamping said engine in position thereon.

FRANK DANIELSON.
